US0D1061032S

(12) **United States Design Patent** (10) **Patent No.:** **US D1,061,032 S**
(45) **Date of Patent:** **** Feb. 11, 2025**

(54) **STORAGE BIN**

(71) Applicant: **Ping Dai**, Cili (CN)

(72) Inventor: **Ping Dai**, Cili (CN)

(**) Term: **15 Years**

(21) Appl. No.: **29/849,270**

(22) Filed: **Aug. 10, 2022**

(51) LOC (15) Cl. **09-04**

(52) U.S. Cl.

USPC **D3/304; D3/315**

(58) **Field of Classification Search**

USPC D6/683, 675, 675.1; D9/517; D3/304, D3/313, 314, 201, 294, 307, 315, 312,

(57) **CLAIM**

The ornamental design for a storage bin, as shown and described.

DESCRIPTION

FIG. 1 is a first perspective view of a storage bin showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIGS. 2; and,

FIG. 11 is an enlarged view of the selected portion 11 in FIG. 6.

The broken lines circumscribe enlarged details.

1 Claim, 11 Drawing Sheets
